(57) **CLAIM**

The ornamental design for an “automotive wheel rim”, as shown and described.

DESCRIPTION

FIG. 1 is a right front top perspective view of an automotive wheel rim in accordance with the present invention;

FIG. 2 is a right front bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom plan view thereof.

The broken line showing is for the purpose of illustrating portions of the automotive wheel rim that form no part of the claimed design.
